APPARATUS FOR FORMING THREADS OR FILAMENTS FROM AQUEOUS DISPERSIONS OF RUBBER OR THE LIKE

Edward Arthur Murphy, Wynde Green, Birmingham, England, assignor to Dunlop Rubber Company Limited, London, England, a British company

Original application February 17, 1933, Serial No. 657,159. Divided and this application April 26, 1934, Serial No. 722,413. In Great Britain April 9, 1932

4 Claims. (Cl. 18—8)

This application is a division of my co-pending application Serial No. 657,159, filed February 17, 1933.

This invention is concerned with improved means of preparing threads or filaments from dispersions of substances in liquid media which tend to sediment or "cream", such as those in which the dispersed materials have different densities from that of the dispersion medium.

10 Dispersions of this kind tend to sediment or settle in an upward or downward direction according to the differences in specific gravity of the continuous and dispersed phases.

15 The object of this invention is to reduce or entirely obviate difficulties due to upward or downward sedimentation of the constituents.

20 In my present invention rubber articles, particularly threads and filaments, are made by supplying suitable aqueous dispersions to a vessel 25 provided with orifices or jets and through which it passes into contact with a setting, coagulating or solidifying liquid and in supplying the dispersion continuously into the vessel in such a way that a constant head of aqueous dispersion is maintained within the vessel and that circulation within the vessel is made continuous by supplying the dispersion thereto in excess of that passed through the orifice, removing in a continuous manner the excess of dispersion from 30 the upper surface of the vessel, and supplying additional dispersion required for filling the vessel to the constant head, preferably at a level substantially adjacent the base thereof.

35 In one embodiment of the invention the plane surface containing the orifices from which the threads are formed is partly immersed in the solution which is used in the ensuing process, and above and below the vessel containing the plane surface in which the jet orifices are situated are 40 positioned two reservoirs, the upper one attached to the vessel by a suitable pipe and controlling means for regulating the flow into the thread-forming vessel, and the lower reservoir being positioned to receive the overflow therefrom.

45 The container or jet box for forming the threads or filaments of rubber from the aqueous dispersions of the kinds hereinafter specified comprises or is in connection with an orifice the bore of which preferably does not exceed two 50 millimetres in length, with an inner tube of such a length as to reach preferably to substantially the base of the container or jet box, and which can be connected with the supply of aqueous dispersions aforesaid and with a drainage outlet, 55 preferably near the top.

The container or jet box is preferably inclined to the vertical and preferably its rear face is provided with the draining orifice, preferably near the top, so that the cream which tends to settle upwards, or other matter such as sediment which has risen to the top, may be continuously removed through the drainage orifice, which is also used to maintain the latex at a constant level or head.

5 The dispersions comprise those consisting of 10 or containing rubber, gutta-percha, balata or similar resins occurring naturally or artificially obtained.

15 Such artificial aqueous dispersions may include those of coagulated rubber, vulcanized rubber, synthetic rubber, waste or reclaim. If desired, any of the aforesaid mentioned dispersions may be used alone or in admixture with one another.

20 Any of the aforesaid dispersions may contain the usual known compounding ingredients 20 and/or may be in concentrated form.

25 Concentrates such as are obtained in Patent No. 1,846,164, February 23, 1932, to which may be added any one or more of the usual compounding ingredients may also be used.

30 The invention may be used in conjunction with the process and apparatus claimed in the specification of Patent No. 1,887,190 and with the device of co-pending application Serial No. 582,769, filed December 23, 1931, but is not limited thereto.

35 In order that the said invention may be clearly understood and more readily carried into effect, the same will now be described more fully by way of example with reference to the accompanying diagrammatic drawing of a part sec- 35 tional side elevation of apparatus for carrying out the invention.

40 The aqueous dispersion of rubber or the like material contained in a reservoir 1 is made to enter continuously a container or thread forming vessel 4 through a connection pipe 2 and a controlling means 3 for regulating the flow via an inner tube held in position by a rubber washer 13 and a nut 14. Before entering the vessel 4 the aqueous dispersion is filtered by a fine muslin gauze 12 also held in position by the rubber washer 13 and the nut 14. The orifice or jets 6 45 of the container 4 are immersed in a bath 5 containing the setting, coagulating or solidifying liquid. Some of the aqueous dispersions of rubber or the like material flows out through the orifice 6, the bore of which preferably does not exceed two millimetres in length, into the settling, coagulating or solidifying bath 5, when it im- 50 55

mediately rises as a solidified thread supported by the setting, coagulating or solidifying liquid.

The inner tube 9 is preferably of such a length as to reach a level 9a substantially adjacent the base of the container 4. In this way it is possible to keep all the liquid within the container 4 in continuous motion.

Most of the liquid leaving 9a rises within the vessel 4 to a constant height 7 from where excess 10 dispersion is removed in a continuous manner from the rear face of the container at 8. Thus the aqueous dispersion of rubber or the like material is made to circulate continuously within the aforesaid vessel or container 4 maintaining a 15 constant head of the aqueous dispersion at 7.

The excess of dispersion removed at 8 is conducted by a pipe 10 to a lower reservoir 11 positioned to receive the overflow.

The plane surface in which the jet orifices 6 20 are situated is preferably inclined to the vertical as shown.

What I claim is:—

1. A container or jet box for forming threads or filaments of rubber from aqueous dispersions

provided with an orifice the bore of which preferably does not exceed two millimetres in length, a setting bath into which said orifice opens, a supply tube of such a length as to reach preferably substantially the base of the container, the container or jet box having an overflow outlet above said orifice and means to convey overflow liquid from said outlet out of contact with said setting bath.

2. A container as claimed in claim 1 wherein 10 the aforesaid overflow orifice is at the rear face of the container.

3. A container or jet box for forming threads or filaments of rubber from aqueous dispersions and having an orifice supplied from said box, a 15 setting bath into which said orifice opens, a supply tube for dispersion extending downwardly within said box to a level below that of said orifice, an overflow outlet above said orifice and means to convey overflow liquid from said outlet 20 out of contact with said setting bath.

4. The apparatus of claim 3 in which said orifice delivers at an oblique angle to the vertical.

EDWARD ARTHUR MURPHY.
